DESIGN FOR A LADY'S EVENING GLOVE OR SIMILAR ARTICLE

Margot Butler, New York, N. Y.

Application November 12, 1941, Serial No. 104,112

Term of patent 3½ years

To all whom it may concern:

Be it known that I, Margot Butler, a citizen of the Republic of France, residing at New York, county and State of New York, have invented a new, original, and ornamental Design for a Lady's Evening Glove or Similar Article, of which the following is a specification, reference being had to the accompanying drawing, forming a part thereof.

Fig. 1 is a rear view of a lady's evening glove showing my new design;

Fig. 2 is a side view of the lady's evening glove shown in Fig. 1; and

Fig. 3 is a front view of the lady's evening glove shown in Fig. 1.

I claim:

The ornamental design for a lady's evening glove or similar article, as shown.

MARGOT BUTLER.
